(57) **CLAIM**

The ornamental design of a bag, as shown and described.

DESCRIPTION

FIG. 1 illustrates a perspective view of a bag according to the first embodiment of the invention with a finger print sensor for opening the lock.

FIG. 2 illustrates a front view of a bag according to the first embodiment of the invention with a finger print sensor for opening the lock.

FIG. 3 illustrates a back view of a bag according to the first embodiment of the invention with a finger print sensor for opening the lock. The back view is on opposite side of the front view.

FIG. 4 illustrates a side view of a bag according to the first embodiment of the invention with a finger print sensor for opening the lock.

FIG. 5 illustrates a side view of a bag according to the first embodiment of the invention with a finger print sensor for opening the lock. The view of FIG. 5 is opposite the view of FIG. 4.

FIG. 6 illustrates a top view of a bag according to the first embodiment of the invention with a finger print sensor for opening the lock.

FIG. 7 illustrates a bottom view of a bag according to the first embodiment of the invention with a finger print sensor for opening the lock.

FIG. 8 illustrates a perspective view of a bag according to the second embodiment of the invention with a combination lock.

FIG. 9 illustrates a front view of a bag according to the second embodiment of the invention with a combination lock.

FIG. 10 illustrates a back view of a bag according to the second embodiment of the invention with a combination lock. The back view is on opposite side of the front view.

FIG. 11 illustrates a side view of a bag according to the second embodiment of the invention with a combination lock.

FIG. 12 illustrates a side view of a bag according to the second embodiment of the invention with a combination lock.

FIG. 13 illustrates a top view of a bag according to the second embodiment of the invention with a combination lock. The view of FIG. 13 is opposite the view of FIG. 12; and,

FIG. 14 illustrates a bottom view of a bag according to the second embodiment of the invention with a combination lock.
